UNITED STATES PATENT OFFICE.

HENRY W. MISHOE AND LEONIDAS W. MANSELL, OF WEST ENFIELD, MAINE.

SELF-PROPELLED SLEIGH.

1,276,246.

Specification of Letters Patent. Patented Aug. 20, 1918.

Application filed February 16, 1915, Serial No. 8,591. Renewed February 8, 1918. Serial No. 216,140.

To all whom it may concern:

Be it known that we, HENRY W. MISHOE and LEONIDAS W. MANSELL, citizens of the United States, residing at West Enfield, in the county of Penobscot, State of Maine, have invented certain new and useful Improvements in Self-Propelled Sleighs; and we do hereby declare the following to be a full, clear, and exact description of the invention, such as will enable others skilled in the art to which it appertains to make and use the same.

This invention relates to a self-propelled sleigh.

An object of the invention resides in the provision of a device of this character wherein the propelling will be accomplished within itself and wherein the shock incident to the riding of the runners over uneven ground will be taken up before being transmitted to the body of the sleigh.

A further object of the invention resides in so constructing the device that the exhaust from the engine will be located so as to prevent the freezing of the operating parts or the clogging of them by snow or ice.

With these and other objects in view, such as will appear as the description progresses, our invention comprises the combination and arrangement of parts as set forth in and falling within the scope of the appended claim.

Referring to the drawing:

Figure 1 is a plan view of a sleigh constructed in accordance with our invention.

Fig. 2 is a side elevation thereof.

Fig. 3 is a fragmental side elevation of the propelling mechanism with the near rear runner and drive wheel casing removed.

Fig. 4 is a vertical sectional view on line 4-4 of Fig. 1, with the casings of the propelling wheel removed.

Fig. 5 is a vertical sectional view on line 5-5 of Fig. 1, showing the manner of mounting the rear runners.

Fig. 6 is a vertical sectional view of one of the bearing members for the runners.

Fig. 7 is a horizontal sectional view of the same.

Fig. 8 is a section taken at right angles to Fig. 7, and likewise in a vertical plane.

Fig. 9 is a side elevation of one of the casings with the covering cap removed and the end of the spindle in section, showing the manner in which the spindle is mounted.

Referring to the drawing wherein like parts are indicated by like characters throughout the several views:—

Our device comprises a chassis 1 on which a suitable body (not shown) is to be mounted. The rear end of this chassis is supported by runners 2 in a manner now to be described.

Secured to the rear axle 3 at each end thereof is a pronged wheel 4 which has an outwardly extending hub 5. This hub extends into a casing 6 which is secured to the adjacent runner, at 7, and is rotatable with relation thereto and also has vertical movement with relation to the casing. This hub 70 extends into a block 8 which terminates at its lower end in a wedge 9. The end of this hub 5 bears against ball-bearings 10 located in a chamber in the block 8. The end of the axle is extended through the block 8 and is 75 engaged by a nut 11 in a slot 12 of the casing 6. This end of the axle moves between ball-bearings 13 in the said slot 12.

A suitable cap 14 is secured over the slot 12. The lower end of each block 8 rests between the beveled ends of sliding blocks 15 which are mounted in chambers 16 in the casing 6 and are pressed inwardly normally toward each other to engage the wedge-shaped end of the block 8 by coil springs 17. 85

The forward end of the chassis is supported by suitable runners 18 which are mounted on the front axle 19 by bearings 20 which preferably include the shock absorbing device described in connection with the 90 bearings for the rear axle. These front runners are provided with a steering rod 21 which may be operated in any suitable manner.

Extending between the front ends of the rear runners and the front ends of the front runners are rods 22 which are made up of a plurality of sections joined together by universal joints 23. An engine 24 is provided which has an exhaust pipe 25. This pipe is 95 provided with diverging arms 26 which terminate adjacent the casings 6 so that the same will be kept warm and consequently ice and snow will be prevented from caking thereon. The propelling wheels 4 are provided with suitable casings 27 to prevent the throwing of snow and ice during the rotation of the same. The bottoms of the runners 2 and 18 are provided with corrugations 28 to prevent skidding. 105 110

In operation as the runners pass over a rough road the shock incident to the movement will be taken up because of the fact that the casings 6 will slide upwardly on the blocks 8 and the sliding blocks 15 will be separated against the tension of the springs 17.

The propelling wheels 4 are provided with chambers 29 in which suitable band brakes are located so that the rotation of the wheels 4 may be prevented and consequently a very effective brake provided.

The tension of the springs 17 may be varied by means of the adjusting screws 30 which operate against collars 31 and are in threaded engagement with the chambers 16. Thus the spreading action of the blocks may be varied.

While we have illustrated and described a particular embodiment of our invention we have merely done so for the sake of convenience and we do not wish to be limited to that particular embodiment as it is obvious that numerous changes may be made in the details of construction thereof without in any way departing from the spirit of

the invention or exceeding the scope of the appended claim.

What we claim is:

In a device of the class described, the combination with a runner, an axle, a drive wheel on said axle, a casing on said runner, a hub on said wheel extending into said casing, a hub block mounted for vertical movement in said casing and a revoluble support on said hub, the lower portion of said block being wedge shape, a pair of oppositely disposed adjusting blocks mounted in said casing and being beveled at their adjacent ends for engagement with the opposite sides of said wedge portion of said hub block, means for adjusting said blocks toward and away from said hub block, and means for rotating said axle.

In testimony whereof we affix our signatures in the presence of two witnesses.

HENRY W. MISHOE.
LEONIDAS W. MANSELL.
